US00D662326S

(12) **United States Design Patent**
Shanbhag et al.

(10) **Patent No.:** US D662,326 S
(45) **Date of Patent:** ** Jun. 26, 2012

(54) **FIBROUS MATERIAL SHEET WITH
PATTERNED SURFACE**

(75) Inventors: **Pramod Shanbhag**, Rocky Hill, CT (US); **V. Richard Annis**, South Windsor, CT (US)

(73) Assignee: **Suominen Corporation**, Tampere (FI)

(**) Term: **14 Years**

(21) Appl. No.: **29/398,014**

(22) Filed: **Jul. 25, 2011**

(51) LOC (9) Cl. **05-05**

(52) U.S. Cl. **D5/49**

(58) Field of Classification Search .... D5/1-4, D5/19, 47, 53, 55-59, 60, 61, 99, 49; D6/582, D6/583, 592, 596, 616, 622; D19/5; D24/124-126; 52/660; 112/401, 416, 439; 139/383 R; 428/32, 37, 39, 66.5, 79, 85, 153, 187, 190

See application file for complete search history.

Primary Examiner — Karen S Acker

(74) Attorney, Agent, or Firm — Nixon & Vanderhye P.C.

(57) **CLAIM**

The ornamental design for a "fibrous material sheet with patterned surface," as shown and described.

DESCRIPTION

The sole FIGURE is a top plan view of a fibrous material sheet with patterned surface showing our new design.

The broken lines around the design indicate the boundaries of the claim and form no part thereof.
